UNITED STATES PATENT OFFICE.

ATHEL E. GOOCH, OF BROCKTON, MASSACHUSETTS.

PASTE-APPLYING MACHINE.

Application filed September 17, 1925. Serial No. 56,877.

This invention relates to improvements in paste-applying machines.

In the manufacture of shoes, for which my improvements are especially adapted, although useful in other arts, it is customary, in some grades and styles of shoes, to apply what is known as a "doubler" to the inner face of the shoe vamp, this being done in what is known as the stitching room of the shoe factory. The doubler ordinarily consists of a piece of cotton fabric having a nap on one side thereof, the side which is applied against the vamp. The object of using the doublers, as is well known, is to permit the use of a lighter and cheaper grade of leather for the vamp, the applied doubler producing the effect of the thicker and more expensive grades of leather for vamps and without detracting from either the appearance or wearing qualities of such more expensive vamps. In practice, it is necessary that the doubler be pasted or cemented to the vamp, and also, it is necessary that the doubler be left fully and freely flexible so as to readily partake of the necessary flexions of the vamp when the shoe is on the wearer.

Heretofore, much difficulty has been encountered in providing the necessary amount of paste or other cementitious substance on the doubler for attachment to the vamp without stiffening of the doubler, due to the paste or the like hardening and imparting undesirable rigidity to the doubler. Experience has demonstrated that the paste or the like, employed for uniting the doubler and vamp, must be applied at relatively widely spaced points and in comparatively minute quantities to the nap of the doubler so that the doubler will be attached to the vamp at a sufficient number of points so as to conform to the shape and movements of the vamp, but without any rigidity or stiffness having been imparted to the doubler.

One object of my invention is to provide a machine of simple and relatively inexpensive construction, which may be operated continuously to efficiently and quickly apply comparatively minute quantities of paste at relatively widely separated points to a fabric or the like and especially to the nap of cotton fabrics used for doublers in the art of shoe manufacture.

More specifically, an object of my invention is a machine of the character generally indicated in the preceding paragraph where-

in is employed an endless conveyor having a path of travel partly within the body of the paste and partly outside of the paste, where-in the conveyor for the paste is of such construction that, automatically, only relatively small or minute quantities of paste are retained at separated points on the conveyor during its travel outside of the body of paste so that, when an operator holds the fabric such as a doubler temporarily in contact with the moving conveyor, only minute quantities of the paste will be applied to the nap of the fabric, the latter then being in proper condition for attachment to the vamp.

A still further specific object of the invention is to provide means for varying the amount of paste which will be applied by a machine of the character above indicated.

Other objects of the invention will more clearly appear from the description considered in connection with the drawings forming a part hereof, and the appended claims following.

In the drawing forming a part of this specification, Figure 1 is a top plan view of a machine having my improvements incorporated therein, parts of one of the cover plates being broken away in order to more clearly illustrate the interior parts. Figure 2 is a vertical, longitudinal, sectional view of the machine and corresponding substantially to the line 2-2 of Figure 1. In both Figures 1 and 2, the endless conveyor is indicated more or less conventionally. And Figure 3 is a detail perspective of a portion of the endless conveyor and showing one approved form thereof.

In said drawings, 10 indicates a suitable container for a quality of paste, the container as shown being preferably of rectangular box-like form having end walls 11-11, side walls 12-12 and bottom wall 13. Mounted within the container and at points relatively near the top thereof and at each end, are two rolls or pulleys 14 and 15, which may be of any suitable construction, but are preferably composed of hollow tubes. Said rolls are carried by suitable journals 16 and 17, respectively, the latter being mounted in suitable bearings 18-18, carried by the side walls of the container. The roller 14 is adapted to be positively driven and for this purpose the journal or shaft 16 thereof is extended at one side of the container and has applied thereto, a gear 19

co-operating with another gear 20, carried by a jack shaft 21, the latter being driven by any suitable outside source of power, as, for instance, an electric motor (not shown).

5 The improved endless conveyor, designated generally by the reference character A, is best shown in detail in Figure 3. As there shown, it comprises a plurality of strands extending lengthwise of the endless conveyor, each strand being composed of a plurality of individual links 22-22. I have found that one suitable form of conveyor may be made of links such as indicated in Figure 3, each link having two eyes 23 and 24, in planes at right angles to each other so that one eye of each link, as, for instance, the eye 23 will extend in a vertical plane, and thereby provide an upstanding rounded, knob-like projection 25. As will be evident, there will be as many knob-like projections 25 as there are links in the conveyor, and such knob-like rounded projections will be spaced at relatively wide distances apart both longitudinally of the conveyor and transversely thereof. The strands are preferably kept the proper distance apart laterally of the conveyor by any suitable means, as, for instance, by transversely extending rods 26, which are soldered or otherwise rigidly attached to a series of links transversely of the conveyor, the spacing rods 26 occurring at suitable intervals longitudinally of the conveyor. With this construction, it is evident that the conveyor 35 may be said to be of relatively wide open mesh and with a series of relatively widely spaced knob-like projections disposed above the central plane of the conveyor proper.

The conveyor A is mounted on the two rollers 14 and 15 so that a portion of the path of travel thereof, as indicated at 27 in Figure 2, is within and through the supply of paste, the level of which will preferably be maintained at somewhere between one-half and two-thirds the height of the container from the bottom. The conveyor is guided upon the rollers 14 and 15, as by suitable annular flanges 28-28 at the ends of the rollers and, if desired, a positive drive may be imparted to the conveyor, by providing suitably spaced cogs 29-29 around the periphery of the roller 14 at each end thereof to engage the outside strands of the conveyor.

To maintain a normal tension upon the conveyor, I preferably provide an idler roller or pulley 30, disposed centrally of the container, said roller having journals 31 at its ends, which work within vertically elongated guideways or bearings 32 at each side of the container so that the weight of the roller 30 is suspended on the bottom portion of the conveyor to maintain the normal tension.

65 As best indicated in Figure 2, a portion of

the path of travel of the conveyor will be horizontal near the top of the container and above or outside of the supply of paste, such portion of the conveyor's travel being indicated at 33. This portion of the path of travel of the conveyor is accessible to the operator who, in the case of doublers, for instance, one of which is partially indicated at 34, will hold the doubler or a portion thereof, with the nap side as indicated at 35, in light contact with the conveyor, the travel of which is in the direction as indicated by the arrow b.

With the construction as thus far described, it will be observed that the conveyor, in passing through the supply of paste, picks up a certain amount thereof on all portions of the links composing the conveyor. As the conveyor passes around the roller 15 and starts on its horizontal travel, it is obvious that the greater quantity of the paste will drip or drain off and only such portions thereof be retained as are held by capillary attraction to the portions of the links. It will further be observed that, in holding the doubler or other fabric in contact with the conveyor, the principal points of contact will naturally occur on the rounded knob-like portions 25 of the individual links so that there will be only a relatively small or minute quantity of the paste applied from each knob-like projection 25 to the doubler and at relatively widely spaced points both longitudinally and laterally of the conveyor.

In practice it is desirable to provide not only a medium of support for the conveyor during its horizontal travel to prevent undue flexing downwardly thereof by the operator, but also, to provide means for governing, to a certain extent, the amount of paste which will be applied to the fabric. For this purpose, I have provided what may be termed a drip table 33', which preferably consists of a flat plate slightly rounded off at its ends as indicated at 33^a to prevent catching against the conveyor. Said table 33' is adjustable vertically within desired limits by any suitable means, one such means comprising depending flanges 34^a at each side of the table, the flanges 34 being slotted as indicated at 35 and receiving therein, bolts or screws 36, whereby vertical adjustment may be effected as will be understood, it being obvious that the bolts 36 are carried by the side walls 12 of the container. By regulating the height of the table 33', I have found that the quantity of paste which will be retained on the uppermost portions of the conveyor can be regulated, the reason for which, as now best known to me, being that a certain quantity of the paste in the form of a film or thin layer will collect on the table, and will retard the draining off of the paste from the

links, depending upon the amount of normal separation between the conveyor and the table prior to the operator applying the fabric in contact with the conveyor.

5 Inasmuch as the pasting machine is normally in use only during the day time, it is desirable to prevent evaporation of the paste when not in use during the night, and for this purpose, I preferably provide covers 36'-36', at each end of the container, which are detachably held in place as by a bayonet slot arrangement 37, the covers 36'-36' being preferably always retained on the machine during operation to prevent 10 fouling with the conveyor and rollers at the ends of the container, and it will be understood that a third section of cover, not shown, will be applied when the machine is closed down, said third section occupying 15 the space between the end sections 36'-36'.

I have employed the term "paste" in a generic sense throughout the specification and hereafter in the claims since this is the term most commonly employed in the shoe 20 manufacturing art. In practice, such paste is of relatively thin consistency and very light. Commonly, it is composed of a mixture of starch, water and animal glue, but it will be understood that the term paste is employed broadly to designate any substance of a cementitious character.

Referring to the particular form of conveyor employed, in addition to the characteristics and functions outlined in the preceding, it will be observed that the conveyor acts as a very efficient agitator for the paste due to the fact that the conveyor is composed of a series of links with knobs or protuberances thereon, and the same will necessarily stir up or agitate the paste in the passage therethrough. Furthermore, the rounded knob-like projections 25 have proven particularly efficient in applying paste to the light nap of a fabric since there are no sharp edges presented and hence, the possibility of catching or pulling out the nap is reduced to a minimum.

The advantages of my machine are that it permits of a rapid application of the paste to the doubler or other article being treated; only the desired and minimum amounts of paste are applied, thereby reducing the quantity of paste required; and by the agitation of the paste produced by the conveyor passing through it, the paste is always maintained in its proper consistency and without caking of the same either on the conveyor or other parts.

60 I have herein shown and described what I now consider the preferred manner of carrying out the invention, and have described the same with particularity with reference to the doublers employed in the manufacture of shoes, but the same is by 65 way of illustration only, and not by way

of limitation, all changes and modifications being contemplated that come within the claims appended hereto.

I claim:

1. In a paste applying machine of the character described, the combination with a suitable container for a supply of paste; of an endless paste conveyor having a path of travel in part through the paste, and in part, outside of the paste, said conveyor being of relatively large open mesh, whereby relatively small amounts of paste are retained thereon at relatively widely separated points both laterally and longitudinally of the conveyor and excess paste drained off in that portion of the conveyor's travel outside of the supply of paste to thereby permit application of small amounts of paste at longitudinally and laterally separated points to a fabric or the like, manually held temporarily in contact with the conveyor; and means for supporting and imparting movement to the conveyor.

2. In a paste applying machine of the character described, the combination with a suitable container for a supply of paste; of an endless paste conveyor having a path of travel in part through the paste and in part outside of the paste, said conveyor being of relatively large open mesh with a knob-like paste-carrying and applying projection at each corner of the mesh, said knob-like projections extending beyond the central plane of the conveyor whereby said knob-like projections are spaced laterally and longitudinally of the conveyor and each is adapted to apply a relatively small amount of paste to a fabric or the like, when manually held temporarily in contact therewith, said open mesh conveyor operating to agitate the paste during the passage of the conveyor therethrough; and means for supporting and imparting movement to the conveyor.

3. In a paste applying machine of the character described, the combination with a suitable container for a supply of paste; of an endless conveyor having a path of travel in part through the supply of paste and in part horizontally outside of the paste; means for supporting and imparting movement to the conveyor; and a flat table disposed in proximity to and under the conveyor in that portion of its path of travel where it travels horizontally, said table being adapted to limit the downward flexing of the conveyor.

4. In a paste applying machine of the character described, the combination with a suitable container for a supply of paste; of an endless conveyor having a path of travel in part through the supply of paste and in part horizontally outside of the paste; means for supporting and imparting movement to the conveyor; and a flat table dis-

posed in proximity to and under the conveyor in that portion of its path of travel where it travels horizontally, said table being adjustable relatively toward and from the conveyor to thereby limit the flexing of the conveyor and govern the amount of paste delivered from the conveyor to the article being pasted, substantially as and for the purpose specified.

10 5. In a paste applying machine of the character described, the combination with a suitable container for a supply of paste; of an endless conveyor having a path of travel in part through the supply of paste, and, in part, outside of the paste in a horizontal path, said conveyor being of relatively large open mesh construction with a knob-like projection at each corner of each mesh whereby relatively small amounts of paste 15 may be applied from said knobs to a fabric or the like at relatively widely separated points; a table disposed beneath the horizontally travelling portion of the conveyor, said table being adjustable relatively toward and from said conveyor to thereby limit the downward flexing of the conveyor; means for supporting said conveyor and

20

25

imparting movement thereto; and means for maintaining a normal tension upon said conveyor.

6. In a paste applying machine of the character described, the combination with a suitable container for a supply of paste; of an endless paste conveyor having a path of travel in part through the paste, and in part, outside of and above the supply of paste, said conveyor being formed with a plurality of laterally and longitudinally spaced, rounded off, relatively small, paste retaining and applying projections, said projections extending above the general plane of the conveyor when in that portion of the path of travel above the supply of paste whereby said projections are adapted to apply individually separated, small amounts of paste to an article, such as a piece of fabric, temporarily and manually held in contact therewith; and means for supporting and imparting movement to said conveyor.

In witness that I claim the foregoing I have hereunto subscribed my name this 10th day of September 1925.

ATHEL E. GOOCH.
